UNITED STATES PATENT OFFICE.

MARSENA R. JULIAN, OF BIRMINGHAM, ALABAMA, ASSIGNOR TO JULIAN SIGNAL COMPANY, OF BIRMINGHAM, ALABAMA, A CORPORATION OF DELAWARE.

BLOCK-SIGNAL SYSTEM.

1,230,903.

Specification of Letters Patent. Patented June 26, 1917.

Application filed April 2, 1913. Serial No. 758,452.

To all whom it may concern:

Be it known that I, MARSENA R. JULIAN, citizen of the United States, residing at Birmingham, in the county of Jefferson and 5 State of Alabama, have invented certain new and useful Improvements in Block-Signal Systems, of which the following is a specification.

My invention relates to block signaling systems, and particularly to track-controlled block signaling systems.

The primary object of my invention is the provision of a block signaling system in which the signaling mechanism is not disposed beside the track, as in the ordinary form of block signal but is carried within the cab of the locomotive and is electrically actuated by the closing or opening of the signal circuits alongside the track, thus reducing the danger present in the ordinary form of block signaling system of the engineer running by the signals, either through inadvertence or by intention.

A further object of the invention is the provision of a block signaling system in which the signaling mechanism is carried in the locomotive cab and is actuated by electrical engagement with certain track contacts operatively connected to certain circuit closing and opening devices actuated by the presence of a train upon another block.

Still another object is to provide means disposed upon a train and actuated by the setting of certain track contacts whereby a clear signal may be given to said train if no train is on a connected block, whereby a cautionary signal may be given if a train is on one of the connected blocks, and whereby a danger signal may also be given if a 40 train is upon a connected block.

Still another object is to provide means operating in connection with the actuation of either the cautionary signal or the danger signal whereby the brakes of the train will be set when either the cautionary signal or the danger signal is given, thus bringing the train to a stop, this mechanism being so constructed that it will require a manual resetting of the mechanism by the engineer in 50 order either to avoid the setting of the brakes or to unset the brakes.

A further object is to provide means whereby the setting of the brakes is accomplished by venting the train pipe upon an actuation of either the cautionary or the 55 danger signals.

A still further object is to provide in connection with the signaling mechanism as above referred to, means whereby a record shall be made of any of the signals received. 60

Another object is to provide means whereby any derangement of the track or signaling circuits will cause the setting of the brakes, and still another object in this connection is to provide means whereby any derangement of the circuits of the signaling mechanism on the cab will cause the setting of the brakes when the train reaches the end of one block and before it enters upon another block. 65

Still another object in this connection is to provide means operating in connection with the clear signal whereby a circuit may be broken to vent the train pipe, unless the track contacts and their connections are operating properly to give a clear signal. 70

A further object in this connection is to provide a cab signaling mechanism including a divided circuit, means disposed in one branch of the circuit adapted to electrically engage with a track contact whereby to actuate the signaling mechanism, and means disposed in the other branch of the circuit adapted to break the circuit through said branch and actuated by mechanical engagement with a track member whereby if no circuit should be completed through the track contact the circuit in the second branch will be mechanically broken, and further in this connection to provide means whereby the mechanical breaking of the circuit through the second named branch will set the brakes on the train unless the circuit has been completed through the first named branch of the circuit. 85

A further object is to provide a contact shoe adapted to engage a track contact, this contact shoe having mounted in conjunction therewith a circuit breaking device adapted to engage a member mounted between the 10 rails of the track, the contact shoe and said circuit breaker being mounted respectively in two branches of a divided circuit. 90

Other objects will appear in the course of the following description. 10

My invention is illustrated in the accompanying drawings, wherein;

Fig. 1 is a perspective view of the cab signaling mechanism.

Fig. 2 is a detail perspective view of the signal recording mechanism.

Fig. 3 is a diagram of the wiring of the

cab signal, the figure also showing a portion of a track and a certain portion of the track system wiring.

Fig. 4 is a diagram of the same character as Fig. 3 but showing the preferable manner of wiring the signaling system on the cab.

Fig. 5 is a side elevation of the clearing contact shoe.

Fig. 6 is a fragmentary plan view of the contact shoe shown in Fig. 5.

Fig. 7 is a detail view of one of the track contact switches used in connection with my signaling mechanism.

Fig. 8 is a detail plan view of one of said switches.

I will first describe the cab signal mechanism. This is illustrated in Figs. 1 and 2. This signaling mechanism is carried upon the engine and is for the purpose of giving either a clear, a cautionary or a danger signal, and in the last two cases automatically applying the brakes. As seen in Fig. 1, I provide three pairs of electro-magnets designated respectively 80^a, 81^a and 82^a, and armatures coacting therewith and designated 84^a, 85^a and 86^a, the armature 84^a operating the clear signal mechanism, the armature 86^a actuating the danger signal mechanism, and the armature 85^a actuating the cautionary signal mechanism.

Disposed in advance of the ends of these armatures is a metallic frame designated 230 which is in the form of an inverted U. The two downwardly extending ends of this frame 230 are connected by means of a cross bar 231, while the upper end of the frame includes a cross piece 230^a. Passing vertically downward through the members 230^a and 231 are the guide rods 232 and slidably mounted upon these guide rods is the slide 233. This slide is ordinarily held in a raised position by means of a spring 234 and formed integral with the slide 233 is an outwardly projecting contact 235 having a downwardly beveled V-shaped head 236 which is adapted to engage with spring contact fingers 237.

Disposed at the middle of the frame are the vertically extending guide rods 238, and slidably mounted upon these guide rods is the slide 239 having the outwardly projecting contact member 240, also provided with a head having bevel faces. This slide 239 is urged downward by means of a spring 239^a. Slidably mounted upon the rods 238 and disposed interiorly of the slide 239 is the slide 241 whose lower end is angularly bent for the passage of the rods 238.

The lower end of the slide 241 is formed with an outwardly projecting arm 242 to which is connected a spring 242^a which is connected at its upper end to the cross bar 230^a and which acts to draw the slide 241 upward. The slide 241 is formed on its rear

edge with a projection 243 formed with an inclined edge. The slide 239 is held in a raised position against the force of the spring 239^a by means of a spring pawl 244 which engages a notch in the slide 239 and this spring pawl will be shifted out of engagement with the slide 239 by means of this incline 243 when the slide 241 is forced downward.

At the opposite end of the frame 230 there are provided the vertical guide rods 245 upon which is slidably mounted the slide 246 which is urged downward by means of the spring 247. This slide has projecting from it a contact member 248 which is insulated from the body of the slide, however, and also has a head formed with downwardly converging or beveled contact faces.

Slidably mounted upon the rods 245 and disposed interiorly of the slide 246 is the slide 249, this slide being urged upward by means of the spring 250 and having a projecting portion 251 with an inclined lower face. The slide 246 is held upward by means of the spring pawl 252 which engages a notch or ratchet tooth in the slide 246 and which is engaged by the inclined edge portion 251 on the slide 249.

The slide 233 is formed with an outwardly projecting arm shown in dotted lines in Fig. 1 and which is designated 254 and which arm extends beneath the extremity of the armature 84^a. When this armature is depressed by the energizing of the magnets 80^a, the slide 233 will be forced downward against the force of spring 234 and this will bring the head 236 into contact with the contact fingers 237 for a purpose to be later stated. The slide 241 is also provided with an outward extension 255 which projects beneath the armature 86^a in position to be engaged thereby upon a depression of the armature. When this armature 86^a is depressed it will force down the slide 241. The inclined face projection 243 will as a consequence come in contact with the pawl spring 244 and force the same out of engagement with the slide 239, whereupon the slide will be drawn downward by means of the spring 239^a, thus bringing the contact member 240 into engagement with a pair of resilient spring contact fingers 256.

The slide 249 is also provided with an outwardly projecting arm 257 which extends beneath the armature 85^a. When this armature 85^a is depressed it will cause the slide 249 to move downward, whereupon the inclined edge projection 251 will engage the pawl 252 and release the pawl from its engagement with the slide 246, whereupon the slide will be drawn downward by means of the spring 247 and the contact member 248 will be brought in electrical engagement with the resilient contact fingers 258.

Disposed so as to project over above the contact piece 240 is a contact finger 259, and projecting over the contact member 248 is a contact finger 260. It will be seen from Fig. 1 that the contact pieces 240 and 248 are normally in engagement with the contact fingers 259 and 260, but that when the slides 239 and 246 are drawn downward by the springs, the contact pieces 240 and 248 will break contact with the fingers 259 and 260 and make contact with the fingers 256 and 258. The slides 233, 239 and 246 are all connected to a generator 271. The contact finger 259 is connected by a wire 261 to the contact member 248. From the double contact fingers 256 extend the wires 262 and 263, the wire 262 extending to the red lamp or danger signal 302 while the wire 263 extends to certain recording apparatus which will be later stated. From the double contact finger 258 extends one wire 264 to a green lamp or cautionary signal and a wire 265 also extends from the contact fingers 258 to the recording apparatus, as will be later stated. From the contact finger 260 extends one wire 266 to the white light or clear signal, and also a wire 267 which extends to certain valve operating mechanism which will be later stated.

The wiring on the locomotive is illustrated in diagrammatic view in Fig. 3. Referring to this diagram *a—a* designate the rails of a track and *C* the trucks of a car, as for instance a locomotive or tender running on these rails. This car carries upon it the three shoes 268, 269 and 270. These shoes are of the form illustrated in Fig. 6. Mounted on the train is the headlight generator or other source of current 271. The shoe 270 is the clear signal shoe and this shoe is connected by means of the conductor 272 to the magnets 80^a, and from these magnets a conductor 273 runs through the signal bell 274 to one side of the headlight generator 271, the other side of the generator being grounded by a conductor 275. The shoe 269 is the danger signal shoe and is connected by means of a conductor 276 to the magnets 81^a and thence by conductor 277 to conductor 273 and thence by way of this conductor to one side of the generator 271. The shoe 268 is the cautionary signal shoe and is connected by means of the conductor 278 to the magnets 82^a and thence by wire 279 to one side of the headlight generator by means of the conductors 277 and 273. It will thus be seen that whenever one of the shoes comes in contact with its appropriate track contact switch, as will be later stated, current will pass from the headlight generator through the corresponding set of magnets 80^a, 81^a or 82^a to the shoe, thence from the track contact switch to the track or to certain relays as will be later described, thus

actuating the corresponding magnets 80^a, 81^a or 82^a, drawing down upon the corresponding armature of said magnet and actuating the appropriate signaling mechanism.

Mounted upon the engine in any suitable position is a train pipe 280, preferably formed with a whistle or other like signal designated 281. This train pipe 280 is provided with a vent valve 282 which is normally closed and which is operated by means of an arm 283 constituting an armature and controlled by electro-magnets 284. These magnets are constantly energized and when energized hold the armature arm 283 in the position illustrated in Fig. 3 but when de-energized permit the armature arm to drop, thus opening the valve, venting the train pipe and putting on the brakes of the train. I do not wish to be limited to any particular means of venting this train pipe as it is obvious that a number of different forms of valve construction might be used, all capable of operation by means of an electro-magnet and all operating in practically the same way.

One side of the generator 271 is connected by means of a conductor 285 to all of the slides 233, 246, 239, and from the finger 260 extends a conductor 267 to these magnets 284. As illustrated in Figs. 1 and 3, the contact members 240 and 248 are normally both in contact with the contact fingers 259 and 260 and thus a slight current is constantly passing from the headlight generator along the conductor 285 through the slide 239 to the finger 259 and thence by wire 261 to the finger 260 and thence by wire 267 to the electro-magnet 284. This magnet 284 is connected by means of conductor 286 to an armature 287 controlled by a constantly energized magnet 288. This armature normally contacts with a conductor 289 which in turn is connected with a second armature 290 normally controlled by an electro-magnet 291 and normally connecting with a ground by a wire 292.

The magnets 288, 291 are constantly energized and as a consequence the wire 286 is normally connected to the ground 292. Thus at all times a current passes from the headlight generator 271 through the magnets 284 to the ground 292. When, however, for any reason this circuit is broken and the magnet 284 is de-energized, the armature 283 will drop and thus vent the train pipe 280 applying the brakes. If the wire leading to the clear shoe should break or be disconnected, the lamp 294 will go out and notify the engineer of the break or disconnection. Magnets 288 and 291 are high resistance magnets and a constant low current flows through them. This current, however, is not sufficient to energize the magnets 81^a, as these are low resistance magnets. If the danger or

cautionary circuit is broken the corresponding relay will apply the brakes. The high resistance magnets 288 and 291 are connected to the contact shoes to insure current flowing through the shoes at all times.

It is, of course, not necessary to apply a brake when a clear signal is received which means that there is nothing on the track ahead, but it is necessary to apply the brakes when either a cautionary signal or a danger signal is received. The magnet 288 is connected by means of the conductor 297 to the cautionary shoe 268. The magnet 291 is connected by means of the conductor 298 to the danger shoe 269. The contact shoe 270 is connected by means of a wire 299 through a lamp 294 to a ground. Each of these magnets 288, 291 are connected to a ground. Inasmuch as each of the shoes 268, 269 and 276 are connected at all times to the headlight generator, a current will pass from the headlight generator through the wires 273, 277 and 279 to the several shoes, and from thence current will return along the wires 297, 298 and 299 to the magnets and so to ground, and the magnets 288, 291 will be constantly energized. It will be understood that the current which thus passes through the magnets 284 and through the magnets 288, 291

25 has not sufficient strength to operate the magnets 80^a, 81^a and 82^a but is of sufficient strength to energize all the other magnets.

In the normal position of the parts as illustrated in the diagram, Fig. 3, a circuit is completed as before explained from the generator 271 by way of wire 285 to and through the slide 239, the finger 259, wire 261, the contact member 248, the finger 260, the wire 267 through the magnet 284 and thence by wire 286 and the several armatures and contacts 287, 289, 290 to the ground 292. If, however, the cautionary shoe, for instance, 268 contacts with a cautionary track contact switch, which is grounded by the means hereafter described, then current will pass from the generator through the cautionary magnets 82^a. This will draw down the armature 85^a forcing down the slide 246 and breaking the connection between the contact member 248 and the finger 260, thus breaking the circuit through the magnet 284 causing the arm 283 to drop, thus setting the brakes.

If the danger shoe 269 strikes a danger track contact member which is connected to the ground as later described, a circuit will be completed through the magnet 81^a drawing down the armature 86^a. This will cause the downward movement of the slide 239 and break the contact between the contact member 240 and the contact finger 259. Thus the circuit will be broken through the magnet 284 and the armature lever 283 will drop. If for any reason these circuits are accidentally broken, the armature lever will

drop, and if for any reason the circuits leading to the magnets 288 and 291 should be broken, the circuit through the magnet 284 would be broken and the armature lever would drop. Thus any derangement of the operative mechanism will cause the putting on of the brakes, or the contact of the appropriate contact shoe with either a danger track contact member or a cautionary track contact member will cause the setting of the brakes.

I have shown a bell 274 placed in the circuit extending between the generator and the clearing magnets 80^a and when a clearing impulse passes through the wires 272 and 273, this bell 274 will be sounded. I have also provided a series of signal lamps designated 300, 301 and 302. All of these lamps are connected on one side to a common ground 303. The clearing signal lamp 300 is a white light and is connected by means of a conductor 266 with the finger 260. As a consequence the current from the headlight generator 271 passes by way of the wire 285 to the slide 239, from thence to the finger 259, the conductor 261, the contact member 248, the finger 260 and the conductor 266 to the white light. Thus the white light is constantly burning when the parts are in normal position, and only upon a depression of either the cautionary slide 246 or the danger slide 239 is this circuit through the white light or clear light broken.

The lamp 301 is green and acts as the cautionary signal. As before stated, one terminal of this lamp is connected to the ground 303 while the other terminal is connected by means of a wire 264 to the contact fingers 258. Thus when the slide 246 is depressed so as to bring its contact member 248 into engagement with the fingers 258, a circuit is completed from the headlight generator by way of wire 285 to slide 239, thence through finger 259, conductor 261, the head 248, the finger 258 and the wire 264 to and through the lamp 301 and back to the ground 303. When the cautionary magnets 82^a are actuated therefore, the green light will be displayed.

The danger light is designated 302 and is red in color and is connected on one side to the ground 303 and on the other side by means of conductor 262 to the contact fingers 256. Thus when the slide 239 is depressed by an energizing of the magnets 81^a, a circuit will be completed from the headlight generator through the wire 285 to the slide 239, thence by the contact member 240 to the contact fingers 256 and thence by wire 262 through the danger light.

The recording apparatus which is illustrated diagrammatically in Fig. 3 is of simple construction. A record tape is used having transversely extending time graduations and having three longitudinally ex-

it will of course be understood that the relay circuits or other mechanisms controlling the grounding of these various contacts will be such that as soon as the track conditions, 5 which were such as would require either being grounded, are changed, their grounds will be broken. As many types of track wiring systems for grounding and opening the grounds of track contacts or for correspondingly operating solenoids or other signaling mechanisms are well known and as no such system forms any part of my present invention, I have not deemed it necessary or advisable to illustrate one.

15 It will be clear that whenever the clear signal shoe 269 engages a grounded clear contact 320, a circuit will be formed from the grounded dynamo 271 through the bell 274, wire 273, magnets 80^a, wire 272 and 20 shoe 269 to the track contact 320 and so to the ground. This circuit will ring the signal bell 274, energize the magnets 80^a and short-circuit the light 294. The energization of the magnets 80^a will cause the slide 233 to move into engagement with the contacts 237 and thus form a circuit from the grounded dynamo 271 through the wire 285, slide 233, contacts 337, wire 310 and magnet 306 to the ground, causing the recorder to 25 record the receipt of a clear signal, while the white light 300 will continue to burn. As soon as the clear signal shoe has passed out of engagement with its contact, the strong circuit through the magnets 80^a will 30 be broken and the bell 274 will, therefore stop ringing, the slide 233 will return to its normal position, breaking the circuit through the magnet 306, and the current will again flow to the light 294. If, on the 35 other hand, the track contact 320, with which the clear shoe engaged, was not grounded, due to the presence of another train within a predetermined distance, no signal would be received and the engineer, 40 because of the absence of the signal, would be warned of existing track conditions.

Going upon the assumption that the track is clear, no danger signals or caution signals will be received and the train will proceed 45 from block to block, receiving the above described clear signal at each block. If, however, there is a train a predetermined distance in advance or at the rear of the train proceeding through a block, whereby the 50 cautionary contact 322 is grounded when the caution signal shoe 269 engages such track contact, the train will be stopped in the following manner. The circuit from the grounded dynamo 271 through the magnets 82^a and wire 278 and caution shoe 268 will 55 be grounded through the track contact 322. As a result, magnet 288 will be short-circuited. The short-circuiting of the magnet 288 will cause the breaking of the circuit 60 through the magnet 284 and the opening

of the valve 282 to vent the train line and stop the train. Furthermore, the circuit through the magnets 284 is additionally opened, due to the energization of the magnets 82^a and movement of the slide 246 out of engagement with the contact 260. This movement of the slide also breaks the circuit through the dynamo 271 through the wire 285, slide 246, contact 260, wire 266 and white light 300 to the ground 303. At 70 the same time, the engagement of the contact 248 of the slide 246 with the contacts 258 establishes a circuit from the dynamo through the wire 285, slide 239, contact 259, wire 261 and contacts 258 which then branches through the wire 264 to the green light 301 and so to the ground and through the wire 265 to the magnet 308 and so to the ground. The green light constitutes a caution signal and the magnet 307 upon its 75 energization operates to record a caution signal. After receipt of this signal, the engineer may, by proper manipulation of the hand lever 503, reset the signaling mechanism and proceed with due care in either direction which he deems advisable.

As soon as the danger shoe 270 comes into engagement with the grounded danger track contact 321, the circuit from the grounded dynamo 277, magnets 81^a and wire 276 to the 80 contact shoe 270 is grounded to energize the magnets 81^a and to short-circuit and thereby de-energize the magnets 291 which were previously energized and to thus break the circuit through the magnets 284 and apply the 85 brakes. Furthermore, the downward movement of the slide 239, caused by the energization of the magnets 81^a, will break any existing circuit to the magnets 284 through the wire 261, contact head 248 and 90 contact 260 and also any existing circuit through these same wires and the wire 266 to the white light 300. Again, this downward movement of the slide will complete a circuit from the dynamo 271 to the wire 95 285, slide 239 and contacts 256 will then branch through the wires 262 and 263 to the red light 302 and magnet 307, respectively, these branch circuits lighting up the red 100 light and causing recording of the danger 105 signal. The engineer can, of course, replace the slide 239 and return the signal mechanism to its original condition. It is obvious that by properly positioning the track contacts suitably connected in track 110 controlled circuits, the system may be adapted for use upon single track lines in which trains run in both directions. I have not, however, so illustrated the contacts in this 115 instance as I shall illustrate such arrangement in describing the modified form of my invention.

The system heretofore described, particularly with relation to Fig. 3, is open to only one objection, that is, that no provision is 120

tending spaces, one for the registration of clear signals, the other for the registration of cautionary signals and the third for the registration of danger signals. As illustrated, the tape 304 is connected to a clock actuated reel and passes beneath a plurality of punches 305. Mounted in conjunction with each punch is a magnet, the three several magnets being designated respectively 306, 307 and 308. Each punch is mounted upon an armature 309 which is hinged at one end and coacts with the corresponding magnet. These magnets are normally de-energized but when energized the armatures are drawn toward the magnets and the corresponding punch 305 will be forced into the strip 304, thus making an indentation upon the strip or otherwise registering the signal thereon.

20 All of the magnets 306, 307 and 308 are connected to a common ground. The magnet 306 is connected by means of the conductor 310 to the contact fingers 237. Thus when the clear signal magnets 80^a are energized and the slide 233 forced downward, a circuit will be completed from the headlight generator by way of wire 285 to the slide 233 which is electrically connected to the wire 285, thence to the fingers 237 and 25 thence by conductor 310 to the magnet 306 operating the corresponding punch and registering the signal upon the tape 304. The magnet 307 is connected on one side to the ground as previously stated and on the 30 other side by means of wire 263 to the contact finger 256. When, therefore, the slide 239 is depressed, circuit will be completed from the headlight generator through the magnet 307 and a danger signal registration will be made upon the strip 304. The 35 magnet 308 is connected by means of the wire 265 to the contact fingers 258 so that upon the energizing of the cautionary signal magnets 82^a, a circuit will be completed 40 from the headlight generator through the magnet 308 and the cautionary signal will be registered.

I have referred to the members 305 as being punches, which implies a perforation 50 of the paper strip 304, but I wish it understood that these members 305 may be in the nature of styli or pens and may merely make a proper mark upon the paper of the recording strip without perforating the 55 same.

As a means for replacing the slides 239 and 246, after receipt of a caution or danger signal, I provide a rock shaft 500 having arms 501 and 502 projecting beneath the 60 lower ends of the slides 239 and 246. This shaft is journaled for rotation, in any manner not shown, and is provided with a hand lever 503 by means of which it may be partially turned to act through its arms 501 65 and 502 to raise the slides.

The track contacts are illustrated in Figs. 7 and 8. Each consists of a rotatably mounted rock shaft 420 and having a normally upwardly projecting arm 421. The shaft is held in its normal position by opposed springs 422 but will rock in either direction upon engagement with one of the train shoes. Projecting from the shaft 420 is a metallic arm 441, and disposed on either side of the rock shaft are the contact members 442 and 443 having resilient contact fingers between which the arm 441 may be inserted. When one of the contact shoes 268, 269 or 270 reaches the contact arm, it rocks the shaft and electrically connects the rock shafts with one of the contacts 442 or 443. In some cases only one of the contact members 443 or 442 is used so that the contact will only operate to electrically connect the rock shaft upon a movement in one direction. Where two contact members 443 and 442 are used, electrical engagement between the rock shaft and the contact members will be secured upon a movement of the rock shaft in either direction.

Disposed at one end of each block are a pair of track contact members or switches designated respectively 320 and 321, the track contact 320 being for the purpose of giving a clear signal while the track contact 321 is for the purpose of giving a danger signal. Disposed at the middle of each block but out of alignment with the contacts 320 and 321 is a track contact 322 designed for the purpose of giving a cautionary signal. These track contact switches are constructed precisely as illustrated in Figs. 7 and 8 and as previously described. The cautionary track contact 322 is a double acting track contact switch while the 105 contact switches 320 and 321 are single acting and only operate by a train running on the track toward the right of Fig. 4.

Before describing the operation of the above described signal system, I wish to point out, in a general way, the operation of the track contacts 320, 321 and 322. Normally the clear track contact 320 is electrically connected to one of the rails or other appropriate ground in such a manner that the presence of a train in blocks a predetermined distance at either side of it will break such connection. On the other hand, the caution track contact and danger track contact 322 and 321, respectively, are normally in open circuits which may be grounded under certain track conditions. For instance, if desired, these circuits may be so arranged that the presence of a train two blocks ahead or two blocks behind, the cautionary track contact will cause grounding of the latter and that the presence of a train within a block, in either direction of the danger track contact 321, will cause grounding of such contact. Furthermore, 130

made whereby if the clear signal wire breaks or the mechanism becomes otherwise deranged, the train would be brought to a stop. In other words, no provision is made so that under all circumstances of a breakdown in the system, the train will be brought to a stop as it is entering one block and previous to entering the other. The cab signal mechanism illustrated in diagram 5 in Fig. 4 is practically the same as that heretofore described, but with the addition of mechanism designed so that if there is anything, no matter what, which will prevent a clear signal being given to the engineer upon 10 leaving one block and before entering the next, the train will be brought to a stop. Even if any of the wiring connections were broken, a danger signal would be given and the train brought to a stop.

15 In Fig. 4, the truck of the tender or other suitable carrier is provided with the three contact shoes 350, 351 and 352. These shoes are of the same form as heretofore described. The shoe 350 is the danger shoe; the shoe 351 is the clearing signal shoe or clear shoe, and the shoe 352 is the cautionary signal shoe.

20 Mounted in the cab of the engine are the three electro-magnets 353, 354 and 355 controlling the armatures 356, 357 and 358, respectively. These armatures in turn control the slides 359, 360 and 361, respectively, in the manner heretofore described. The magnets 353 are the magnets controlling the cautionary signal; the magnets 354 control the clearing signal, and the magnets 355 control the danger signal.

25 The slide 360 is provided with the contact member 360^a and the slide 359 is provided with the insulated contact member 362. The contact member 362 is electrically connected by means of the wire 363 with a finger 364 which is normally in contact with the contact 361^a. The contact member 362 is normally in contact with the finger 365. Disposed below the contact member 362 are the contact fingers 366, and disposed below the contact member 361^a are the contact fingers 367.

30 Carried by the slide 360 is the contact member 360^a adapted when lowered to electrically engage with the contact fingers 369. The contact finger 365 is connected to the clear signal light 372 by wire 373. The lamp 372 is connected to a ground 374. The cautionary signal light is designated 370 and is connected by means of wire 371 to the contact fingers 366 and to the ground 374 to which the lamp 370 is also connected. The contact fingers 367 are connected by means 35 of a wire 375 to a danger signal lamp 376 which is also connected to the ground 374.

35 A generator 377 is connected on one side to a ground and on the other side by means of a conductor 378 to the three several slides 359, 360 and 361. The generator is also con-

nected by means of the conductor 379 to the danger signal magnets 355, which in turn are connected by means of wire 380 to the danger signal shoe 350. The generator 377 is also connected by means of the conductor 381 to the magnets 353 of the cautionary signal and these magnets are in turn connected by means of a conductor 382 to a cautionary shoe 352.

40 The clearing signal shoe 351 is connected by means of a wire 383 to the magnets 354. Thence the circuit passes by means of a conductor 384 to and through a signal bell 385, thence to a conductor 386^a which has a terminal 387 electrically engaging an armature 388 which in turn is connected to a contact terminal 389 normally in engagement with an armature 390. From this armature 390 a conductor 391 leads through magnet coils 392 and to a contact member 393. The armature 394 of the relay 392 has a bridging contact 395 which normally closes a circuit between the finger 393 and a finger 396. This finger is connected by means of a conductor 397 to and through the coils 398 of a valve 399, this armature operating an air vent valve 400 in a train pipe 401. From the magnets 398 extends a conductor 402 which is connected to the finger 365.

45 The armatures or circuit breakers 388 and 390 are controlled by means of magnets 403 and 403^a in a manner previously described. These magnets are each connected on one side to a ground. On the other side the magnet 403 is connected by means of a conductor 404 to the danger shoe 350 while the magnet 403^a is connected by means of the conductor 405 to the cautionary shoe 352.

50 The conductor 386 is connected to one member 407 of a contact jaw 406 mounted upon the shoe 351 or in any other convenient position. The other member 408 is mounted in conjunction with the member 407 but insulated therefrom. Rotatably mounted in the shoe 351 is a rock shaft 409 having an arm 410 which when inserted between the members 407 and 408 is adapted to electrically connect the same, the member 408 being connected by a wire 411 to a ground 412. The rock shaft 409 is provided with a depending arm 413 and springs are provided on each side and designated 414 whereby the depending arm is yieldingly supported in a vertical position. It will be obvious now that when this arm 413 is struck it will be rotated and the arm 410 will be removed from its engagement with the contacts 407 and 408, thus breaking the circuit through these contacts and thus breaking the circuit through the wire 386. Two of these circuit breakers are provided, one at either side of the shoe 351 in order that one or the other of them may be operated by a single contact rail in a single track system in which trains

pass in both directions along the same track, irrespective of the direction in which the train is passing.

Disposed between the track rails are the several track contact switches 415, 416 and 417. The contact switch 417 is the cautionary contact switch and is disposed at the middle of the block. The contact switches 415 and 416 are the same as those heretofore described and are disposed at the end of one block just prior to the entrance of the other block. The wiring connections of these contact switches are similar to those heretofore described and illustrated in Fig. 3.

In Fig. 4, as will be noticed, I have illustrated one entire block and a part of another block and in addition to the above track contact switches I have also shown reversely arranged track contact switches 415^a, 416^a and 417^a which operate in connection with trains going in one direction along the track, while the previously described contact switches operate with trains going in the other direction along the track. All of these contact switches, with the exception of the contact switches 415 and 415^a, are of the single type arranged to operate only upon a train going in one of two directions, while the switches 415 and 415^a are arranged to operate irrespective of the direction in which the train is going. The switch 415 is so wired that under clear conditions it is always grounded as regards a train going from left to right, while the switch 415^a is so wired as to be always grounded under clear conditions for a train going from right to left. The wiring of the switches 415^a, 416^a and 417^a is, aside from this difference, identical with the wiring of the switches 415, 416 and 417.

Disposed parallel to the rails and adjacent to the contact switches 415 and 415^a which are the contact switches for actuating the clear signal mechanism is a rail 418. Preferably this rail has inclined ends. This rail is less in length than the corresponding shoe 351 and preferably is only about three-fourths as long as this shoe. It is so disposed that the contact switches 415 and 415^a are at the middle of this rail. This rail is so disposed that it will engage one of the depending arms 413 and rotate it to a position to break the circuit through the wire 386.

The operation of the system shown in Fig. 4 is the same as heretofore described. Assuming that the train has entered the block from the right hand end of the drawing in Fig. 4, then if the track ahead is clear, when the contact shoe 352 reaches the cautionary track contact switch 417, no cautionary signal will pass. Now when the train reaches the contact switches 415 and 416, assuming that there is no train ahead, the shoe 352 will engage the contact switch 415 prior to the engagement of the rail 418

with the arm 413. When the arm 413 reaches the rail it will be turned and the circuit through the wire 386 will be broken, but prior to this time the shoe 351 will have engaged the upwardly extending arm of the contact 416 and therefore a circuit will be completed through the shoe 351 by way of wire 383 through the magnets 354, through the bell 385, through conductor 386, through the circuit breaking armatures 388 and 390, through the magnet 392, from thence through the contact fingers 393 and 396 and the bridging piece 395 to wire 397, thence through the magnet 398, thence by way of wire 402 to the finger 365, thence to the contact piece 362, thence by wire 363 to the contact finger 364, thence to the slide 361, thence by wire 378 to the generator and thence to the ground. This will cause an actuation of the armature lever 357 and the closing of the circuit through the recording apparatus (not shown).

It will be noted that there is normally current flowing at all times through the magnets 392 and 398 by way of the wire 378, slide 361, finger 364, wire 363, contact 362, finger 365, wire 402, wire 397, the contact fingers 396 and 393, through the magnet 392, thence by wire 391 and 386 to the contact members 407 and 408 and to the ground 412. This keeps these magnets 392 and 398 energized. The activity of the magnet 398 holds the armature lever 399 in position to close the vent valve and the activity of magnet 392 holds the plug 395 in place between the contact fingers 393 and 396.

Assuming that there is no train on the track ahead but that some derangement of the mechanism has occurred, either by the cutting or breaking of the track circuits, or the breaking of any of the circuits in the cab signaling mechanism, then when the shoe 351 on the train engages with the track contact switch 415, no circuit will be made. This will prevent a clear signal being given, but the omission of this clear signal may not be noticed by the engineer and the train might run on into the next following block and into danger. It is to avoid this that I have provided the rail 418 and the circuit breaker formed by the parts 413, 410, 407 and 408. When the arm 413 contacts with the rail 418, the circuit through the contact members 407 and 408 will be broken and the circuit through the magnets 398 and 392 will be broken in two places. It will be broken through the contacts 407 and 408 and will also be broken through either wire 383. The breaking of the circuit through wire 386 or 383 will deenergize the magnets 392, whereupon the armature 394 thereof will drop, breaking the circuit through the magnet 398, causing the armature 399 to drop and the setting of the brakes. The object of providing the magnet 392 and the plug 120

395 is to compel the engineer to manually reestablish the circuit through the magnets 398 before he can release the brakes.

It will be noted that if the track circuits have been set to danger, it will be impossible to get a clear signal, and if now any of the wires of the track system break, the same operation will be performed as just previously described, that is, the arm 413 will strike the rail and will break the circuit through the magnet 398 causing the train to be brought to a stop. Any derangement of the cab apparatus which would place the train in danger of running into a block already occupied, will also cause a breaking of the circuit through the magnet 398 and cause the setting of the brakes. The breaking of the circuits leading through the relay magnets 403 and 403^a would also cause a breaking of the circuit through the magnets 392 and 398 which would cause the train to be brought to a stop.

It will of course be understood that trains going in the opposite direction along the track will operate the contact switches 415^a, 416^a and 417^a in the identical manner above described.

In Fig. 4 the connections to the recording apparatus have not been shown inasmuch as these connections are precisely the same as heretofore described and do not in any way affect the operation of setting the brakes. The system illustrated in Fig. 4 is the preferable system inasmuch as it is a system wherein all accidents are provided for and wherein any derangement of the track circuits or of the cab signal circuits will cause the application of the brakes.

It will be seen that with my improved cab signal system not only is the engineer warned by a visual signal of a clear block or of danger, but he is also warned by means of the blowing of the whistle on the train pipe and furthermore in case this warning should be unheeded by the engineers, provision is made whereby the brakes may be thrown on, and it can only be thrown off by intentional manual actuation of lever 503 by the engineer.

Again provision is made for recording the signals received by the engineer which will also record the time spent by the engineer waiting (with the shoes of the engine upon the danger and clearing track contacts) for a clear signal.

By the terms "vehicle" and "train," as employed in the claims, I intend to indicate any vehicle or connected vehicles adapted to travel upon track rails, such as a locomotive, a locomotive and its tender or what is commonly known as a train including a locomotive, tender and one or more cars.

What I claim is:

1. In an electric block signal system, a vehicle having thereon a source of energy,

a shoe adapted to engage a grounded track contact, said shoe being electrically connected in circuit to the source of energy, electrically operated brake actuating mechanism normally in circuit with the source of energy, means actuated by the engagement of the shoe with the track contact for connecting the actuating mechanism in a second circuit with the source of energy, a signal, means actuated by the engagement of the shoe with the track contact for electrically connecting the signal in circuit with the source of energy, and mechanically operated means for breaking the first circuit through the brake actuating mechanism. 75

2. A block signal system including a shoe adapted to be electrically engaged with a track contact, a signal actuating magnet, a source of energy, a circuit closer connected on one side to said source of energy and when closed connecting with the ground, and a magnet controlling the circuit closer and when energized holding the circuit closer to the ground, said magnet being connected through the shoe with the source of energy, 90 said shoe being connected through the actuating magnet with the source of energy, the actuating magnet having less resistance than the magnet controlling the circuit closer. 80

3. In a track controlled block signaling system, a train-carried signal mechanism including a signal actuating magnet, a source of energy, a brake controlling magnet in circuit with the source of energy, a magnetically controlled circuit closer, the magnet of which is in a normally closed circuit with the source of energy, said circuit closer normally closing the brake magnet circuit, a branch connected to said latter circuit and extending through the signal actuating magnet, a contact shoe connected thereto and adapted to engage with a track contact, and mechanically actuated means for breaking the brake controlling circuit, said means being disposed in said circuit between the ground and the junction of the branch circuit. 100

4. In a block signal system, a train-carried mechanism including a constantly energized, brake-controlling magnet, mechanical means for breaking the circuit through the brake-controlling magnet, electrical means for holding said circuit completed, means disposed in the track for electrical engagement with said electrical holding means to ground the latter, and means disposed in the track for engaging said circuit breaking means to cause it to break said circuit. 115

5. In a block signal system of the character described, the combination with a grounded track contact, of a train carried signal mechanism including a constantly energized brake-controlling magnet, a contact shoe electrically connected in circuit 125

- with the magnet, a grounded branch connection forming part of the magnet circuit, a circuit breaker mounted in conjunction with the shoe and disposed in said branch,
- 5 and an actuating rail disposed in the track adjacent to the track contact and adapted to engage said circuit breaker to actuate the latter after the contact shoe has electrically engaged the track contact.
- 10 6. In a block signal system of the character described, the combination with a grounded track contact and an actuating rail extending on both sides of the contact, of a train-carried signal mechanism including a constantly energized brake-controlling magnet, a contact shoe adapted to electrically engage the track contact, said shoe being electrically connected to the circuit of said magnet, a grounded branch connection
- 15 forming part of the magnet circuit, and a circuit breaker disposed in said branch and normally held in position to complete a circuit through the branch, said circuit breaker including a member adapted to be engaged
- 20 and shifted by the actuating rail to a position to interrupt said grounded circuit.
7. In a block signaling mechanism, the combination with a train-carried, longitudinally extending shoe having a conductor
- 25 leading therefrom, spaced contacts carried on the shoe and insulated therefrom, one of said contacts being grounded, a conductor leading to the other contact, a rock shaft having an arm adapted when the shaft is
- 30 turned to one position to establish electrical connection between said contacts and to other positions to break such connection and a downwardly projecting arm carried by the rock shaft, of a track contact member with
- 35 which the shoe is adapted to engage, and an actuating rail extending longitudinally on each side of the track contact member, less in length than the contact shoe and adapted to engage the depending arm and actuate
- 40 the rock shaft.
8. In a block signal system of the character described, train-carried signaling mechanism including, danger, clear and cautionary track contact shoes, danger, clear and
- 45 cautionary magnets electrically connected to the respective shoes, danger, clear and cautionary signaling mechanism operated by said magnets, brake actuating apparatus including an armature and a brake controlling magnet, means for normally holding the armature to the brake controlling magnet, means for breaking the circuit through the break controlling magnet upon the actuation of a cautionary signal mechanism,
- 50 means for breaking the circuit through the brake controlling magnet upon an actuation of the danger signal mechanism, and means for breaking the circuit through the brake controlling magnet upon a derangement of the actuating mechanism.
9. In a block signal system of the character described, train-carried signaling mechanism including a source of electrical energy, danger, clear and cautionary contact shoes, danger, clear and cautionary magnets electrically connected to the respective shoes on one side and to the source of energy on the other, danger, clear and cautionary signaling mechanisms operated by
- 70 said magnets, brake actuating apparatus including a magnet in constant circuit with the source of energy and an armature coacting with the magnet, means for breaking the circuit through the last named magnet upon the actuation of the cautionary signaling mechanism, means for breaking the circuit through said magnet upon an actuation of the danger signaling mechanism, and means for breaking the circuit through the magnet upon a derangement of the actuating mechanism and when no electrical impulse is received through the clear contact shoe.
- 75 10. In a block signal system of the character described; train-carried signaling mechanism including a source of electrical energy, danger, clear and cautionary contact shoes, danger, clear and cautionary magnets electrically connected to the respective shoes on one side and to the source of energy on the other, danger, clear and cautionary signaling mechanisms operated by
- 80 said magnets, brake actuating apparatus including a magnet in constant circuit with the source of energy and an armature coacting with the magnet, means for breaking the circuit through said magnet upon an actuation of the danger signaling mechanism, and means for breaking the circuit through the magnet upon a derangement of the actuating mechanism and when no electrical impulse is received through the clear contact shoe.
- 85 11. In a block signal system of the character described; train-carried signaling mechanism including a source of electrical energy, danger, clear and cautionary contact shoes, danger, clear and cautionary magnets electrically connected to the respective shoes on one side and to the source of energy on the other, danger, clear and cautionary signaling mechanisms operated by
- 90 said magnets, brake actuating apparatus including a magnet in constant circuit with the source of energy and an armature coacting with the magnet, signals for each of the danger, clear and cautionary signaling mechanisms adapted to be placed in circuit with said source of energy upon an actuation of their respective signaling mechanisms, means for breaking the circuit through the brake actuating magnet upon the actuation of either the cautionary or danger signaling mechanisms, means for
- 95 breaking the circuit through the brake controlling magnet upon a derangement of the signal actuating circuits, and means for breaking the circuit through the brake controlling magnet if no electrical impulse is received through the clear contact shoe.
- 100 12. In a block signal system cab equipment, a source of electrical energy grounded on one side, an electrical brake controlling mechanism, a normally closed circuit including the source of energy and brake controlling mechanism, a track obstacle engaging circuit breaker in the circuit, a relay, which, when deenergized, breaks the circuit, a contact shoe adapted to be engaged by a track contact, and a circuit through the
- 105 source of energy, contact shoe and relay which is normally closed the relay being short circuited when the contact shoe engages a grounded track contact.
- 110 13. In a block signal system cab equipment, a source of electrical energy grounded on one side, an electrical brake controlling mechanism, a normally closed circuit including the source of energy and brake controlling mechanism, a track obstacle engaging circuit breaker in the circuit, a relay, which, when deenergized, breaks the circuit, a contact shoe adapted to be engaged by a track contact, and a circuit through the
- 115 source of energy, contact shoe and relay which is normally closed the relay being short circuited when the contact shoe engages a grounded track contact.
- 120 14. In a block signal system cab equipment, a source of electrical energy grounded on one side, an electrical brake controlling mechanism, a normally closed circuit including the source of energy and brake controlling mechanism, a track obstacle engaging circuit breaker in the circuit, a relay, which, when deenergized, breaks the circuit, a contact shoe adapted to be engaged by a track contact, and a circuit through the
- 125 source of energy, contact shoe and relay which is normally closed the relay being short circuited when the contact shoe engages a grounded track contact.
- 130 15. In a block signal system cab equipment, a source of electrical energy grounded on one side, an electrical brake controlling mechanism, a normally closed circuit including the source of energy and brake controlling mechanism, a track obstacle engaging circuit breaker in the circuit, a relay, which, when deenergized, breaks the circuit, a contact shoe adapted to be engaged by a track contact, and a circuit through the

ment, a source of electrical energy grounded on one side, an electrical brake controlling mechanism, a normally closed circuit including the source of energy and brake controlling mechanism, a track obstacle engaging circuit breaker in the circuit, a relay, which, when deenergized, breaks the circuit, a contact shoe adapted to be engaged by a track contact, a circuit through the source of energy, contact shoe and relay which is normally closed the relay being short circuited when the contact shoe engages a grounded track contact, and a signal adapted to be operated upon the short-circuiting of the relay.

13. In a block signal system cab equipment, a source of electrical energy grounded on one side, an electrical brake controlling mechanism, a normally closed circuit including the source of energy and brake controlling mechanism, a track obstacle engaging circuit breaker in the circuit, a second circuit forming a branch of the first, a relay common to both the first circuit and branch circuit and adapted, when deenergized, to open both circuits, and a track contact engaging shoe included in the branch circuit and adapted, upon engagement of a grounded track contact, to maintain the branch circuit through the relay.

14. In a block signal system cab equipment, a source of electrical energy grounded on one side, an electrical brake controlling mechanism, a normally closed circuit including the source of energy and brake controlling mechanism, a track obstacle engaging circuit breaker in the circuit, a second and normally open circuit through the source of energy and brake controlling mechanism, and a contact shoe in the second circuit adapted, upon engagement with a grounded track contact, to close the second circuit.

15. In a block signal system cab equipment, a source of electrical energy grounded on one side, an electrical brake controlling mechanism, a normally closed circuit including the source of energy and brake controlling mechanism, a track obstacle engaging circuit breaker in the circuit, a second and normally open circuit through the source of energy and brake controlling mechanism, a contact shoe in the second circuit adapted, upon engagement with a grounded track contact, to close the second circuit, a relay

having its contacts common to both circuits 55 and adapted, when deenergized, to open both circuits, a normally closed circuit including the relay, and a contact shoe in said latter circuit adapted, upon engagement with a grounded track contact, to short circuit the 60

16. In a block signal system cab equipment, a source of electrical energy, a caution contact shoe, a danger contact shoe, a caution relay, a danger relay, a circuit including 65 the source of electrical energy, the caution contact shoe and caution relay, a circuit including the source of electrical energy, the danger contact shoe and the danger relay, an electrical brake controlling mechanism, a 70 normally closed circuit including the source of energy and brake controlling mechanism, a track obstacle engaging circuit breaker in the latter circuit, the relays each being adapted, when deenergized to open the latter circuit, a clear contact shoe, and a normally open circuit through the source of energy and clear contact shoe adapted to be closed by grounding of the clear contact shoe, said latter normally open circuit also 80 including the brake controlling mechanism and also being controlled by the relays.

17. In a cab signal system, clear, danger and cautionary signals, a source of electrical energy, separate circuits connecting each of 85 the signals with the source of energy, track contact controlling means for breaking or closing a circuit through any one of said signals, electrical brake actuating means electrically disconnected from the source of energy upon the establishment of a circuit through either the danger or cautionary signal, controlling circuits for the cautionary and danger signal circuits, a pair of normally energized high resistance magnets disposed in the cautionary and danger controlling circuits, and circuit closers controlled by said magnets disposed in a circuit leading from the source of energy to the brake actuating means for applying the brakes 90 95 upon the deenergizing of said magnets.

In testimony whereof I affix my signature in presence of two witnesses.
